UNITED STATES PATENT OFFICE.

JOHN CLIFFORD MILLER, OF CINCINNATI, OHIO.

DESIGN FOR AN EMBLEM OR SIMILAR ARTICLE.

47,387.

Specification for Design.

Patented May 25, 1915.

Application filed January 18, 1915. Serial No. 2,991. Term of patent 3½ years.

To all whom it may concern:

Be it known that I, JOHN CLIFFORD MILLER, a citizen of the United States, and residing at Cincinnati, in the county of Hamilton and State of Ohio, have invented a new, original, and ornamental Design for Emblems or other Similar Articles, of which the following specification is a full disclosure.

My invention relates to a new, original and ornamental design for emblems or similar articles.

The features of the design are shown in the accompanying drawing forming a part of this specification and comprising a disk having a matted surface, there being displayed in the medial portion thereof a shield, with superposed books and a lamp and a ribbon-like scroll extending transversely to the lamp.

Having described my invention, I claim:

The ornamental design for an emblem or similar article, as shown and described.

In witness whereof, I hereunto subscribe my name, as attested by the two subscribing witnesses.

JOHN CLIFFORD MILLER.

Witnesses:

L. A. BECK,
EMMA SPENER.
